UNITED STATES PATENT OFFICE.

HERBERT L. HOLT, OF SMUGGLER, COLORADO.

ROTARY-TOOL HOLDER.

1,198,919.

Specification of Letters Patent. Patented Sept. 19, 1916.

Application filed December 17, 1915. Serial No. 67,389.

To all whom it may concern:

Be it known that I, HERBERT L. HOLT, a citizen of the United States, residing at Smuggler, county of San Miguel, and State of Colorado, have invented certain new and useful Improvements in Rotary-Tool Holders; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in means for washing and drying utensils such as dishes and the like, and my object is to present a portable device of this character having a brush mounted upon one extremity 20 and its opposite extremity adapted to be connected with suitable means for rotating said brush, whereby both the aforesaid washing and drying functions may be performed.

25 Another object of my invention is to so construct the device that the elements which compose the same may be readily detached from each other for cleaning or other purposes.

30 Having briefly outlined my improved construction, I will proceed to describe the same in detail, reference being made to the accompanying drawing, in which is illustrated an embodiment thereof.

35 In this drawing:—Figure 1 is a longitudinal sectional view of my improved device with the parts assembled. Fig. 2 is a longitudinal sectional view of the device with the end pieces or caps detached.

40 The same reference characters indicate the same parts in all the views.

Let the numeral 5 designate a shaft having spaced shoulders 6 and 7 formed thereon, the said shaft adapted to be journaled within a shell or casing 8 composed of hard rubber or other suitable material. This shell 8 is composed of a body part 9 and detachable end pieces or caps 10 and 12. The extremities of the said body portion of the shell are interiorly threaded at 13 to receive bearings 14 and 15 which are exteriorly threaded for this purpose, said bearings also having openings or recesses 16 formed in their outer ends, whereby they may be readily detached from the body portion 9 of the shell by means of a spanner wrench.

The shaft 5 is journaled in these bearings and the inner ends of the latter are adapted to respectively engage the shoulders 6 and 7 formed upon the said shaft. The bearings 60 extend beyond the opposite extremities of the body portion 9 for approximately half their length and upon these extensions are screwed the caps 10 and 12 respectively, which are interiorly threaded as shown at 65 17. The opposite extremities of the shaft 5 project beyond the ends of the shell 8 through perforations 18 and 19 formed in the respective caps and the forward extremity of the said shaft is reduced and 70 formed rectangular in shape as shown at 20 while its rear extremity is exteriorly threaded as illustrated at 21. Upon the said reduced extremity 20 of the shaft is mounted a brush holder 22 provided with a sleeve 75 23 whose interior is shaped to correspond with the said reduced extremity of the shaft 5. The inner end of the sleeve will abut against a shoulder 24 formed adjacent the rectangular portion of the shaft, and the 80 holder 22 will be secured in place by means of a thumb-screw 25 mounted in the sleeve 23 and whose inner extremity is adapted to engage one face of the said rectangular portion 20. The outer extremity of the brush 85 holder is reduced and exteriorly threaded as shown at 26, and upon which threaded portion is screwed a brush 27. The brush illustrated in Fig. 1 of the drawing is only one of many types which may be employed, 90 the selection of the brush depending upon the character of the work to be performed. Also, the connection between the brush and the forward extremity of the shaft may be varied as circumstances may require, the 95 construction disclosed upon the drawing merely being a convenient manner for forming the said connection.

In employing the above described apparatus the rear threaded extremity 21 of 100 the shaft 5 is connected with a flexible shaft (not shown) adapted to be rotated by an electric motor or other suitable means, whereby the shaft 5 and the brush 27 will have a corresponding movement imparted 105 thereto. During the operation of this device the shell or casing of the latter is gripped in the hand of the user, whereby the apparatus is portable, and utensils of all descriptions may be washed and dried. 110

Attention is called to the fact that the device can be readily taken apart for clean-

ing purposes or for the replacing of any part which may become worn or injured.

Having thus described my invention, what I claim is:—

5. 1. An article of the class described comprising a cylindrical casing composed of a body portion and end pieces, a bearing located within each end of the said casing, the body portion of the latter being detachably connected with both bearings and the end pieces being detachably connected with the respective bearings, a shaft journaled within said bearings and the extremities of the said shaft projecting beyond the opposite ends of the casing through openings formed in the end pieces, one extremity of said shaft adapted to support a tool while its other extremity is adapted to be connected with means for rotating the same.
10. 2. An article of the class described comprising a cylindrical casing composed of a body portion and end pieces, a bearing located within each end of the said casing,
15. 3. An article of the class described comprising a casing composed of a body portion and end pieces, a bearing screwed into each extremity of the body portion and the end pieces adapted to be screwed upon the respective bearings, a shaft journaled within said bearings, one extremity of the said shaft adapted to support a tool while its other extremity is adapted to be connected with means for rotating the same.

the extremities of the body portion of the latter being interiorly threaded and detachably connected with both bearings and the end pieces being detachably connected with the respective bearings, a shaft journaled within said bearings and the extremities of the said shaft projecting beyond the opposite ends of the casing through openings formed in the end pieces, one extremity of said shaft adapted to support a tool while its other extremity is adapted to be connected with means for rotating the same.

35. 4. An article of the class described comprising a casing composed of a body portion and end pieces, a bearing screwed into each extremity of the body portion and the end pieces adapted to be screwed upon the respective bearings, a shaft journaled within said bearings, one extremity of the said shaft adapted to support a tool while its other extremity is adapted to be connected with means for rotating the same.

40. In testimony whereof I affix my signature in presence of two witnesses.

HERBERT L. HOLT.
